GARMENT HANGER

Joel Schlank, Jersey City, N. J.

Application July 3, 1945, Serial No. 603,065

5 Claims. (Cl. 223—95)

1

My invention relates to means for supporting or suspending garments, and the same has for its object the provision of a hanger which is simple in construction, efficient in use, and inexpensive to manufacture.

Further, said invention has for its object the provision of a garment hanger which may be conveniently secured upon a door, wall or other suitable rigid support, and which may be readily adjusted to operative and inoperative position.

Further, said invention has for its object the provision of a garment hanger which, when adjusted to horizontal or garment supporting position, will maintain the garment in distended form in order to facilitate drying or airing thereof.

Further, said invention has for its object the provision of a garment hanger preferably formed of wire of appropriate gage, and which includes a support or bracket member, and a resilient loop-member which is pivotally secured to the support or bracket member, and capable of being readily adjusted to and from horizontal or garment-supporting position.

Other objects will in part be obvious and in part be pointed out hereinafter.

To the attainment of the aforesaid objects and ends my invention consists in the novel features of construction, and in the combination, connection and arrangement of parts hereinafter more fully described and then pointed out in the claims.

In the accompanying drawings:

Figure 1 is a perspective view showing one form of hanger constructed according to and embodying my said invention;

Fig. 2 is a plan view showing the hanger secured to a rigid support or wall;

Fig. 3 is a side edge view, looking in the direction of the arrow A, Fig. 2, and

Fig. 4 is a detail perspective view showing another form of attaching device for the garment.

In said drawings 10 designates a supporting bar or bracket formed of heavy gage wire and provided with offset ends 11 which are bent forwardly, outwardly, and inwardly to form in-turned ends 11a, and disposed in a horizontal plane coinciding with that of the intermediate portion of said bar or bracket. The bar or bracket 10 is provided inwardly of the ends 11 with flattened portions 12 having apertures to receive screws or fastening devices 13 for securing the bar to a suitable rigid support 14.

15 denotes a substantially circular, resilient supporting loop, also formed of wire having overlapping end portions 15a, 15b terminating in

2

rearwardly-extending end portions 16a, 16b provided with eyes 17a, 17b which embrace the offset portions 11 of the bar 10.

The rearwardly-extending end portions 16a, 16b are maintained normally spread apart and against the offset ends of the bar 11, and rest upon the inturned ends 16a, 16b by the tension of the resilient loop 15 when said loop is adjusted to horizontal or garment supporting position.

The loop 15 is provided with a series of garment attaching devices each of which comprises a member 18, having a ring or eye 19 at its upper end disposed upon the loop member 15, and a pointed end hook 20 at its lower free end to engage with the upper edge of the garment. The attaching devices are maintained in duly spaced relation upon the loop 15 by means of ears or small projections 21 struck up from the body 20 of the loop at the sides of each ring or eye 19.

At Fig. 4 the attaching device comprises a pair of clamping jaws 25 held under tension by a spring 26, and provided with arms 27 each having an opening 28 in the end thereof to receive the ring 29 whereby the device may be secured to the loop 15, and serve to support or suspend the garment on said loop.

The operation of the hanger will be largely obvious from the foregoing specification. It need only to be noted that normally the loop 15 will be supported in vertical position as indicated by broken lines at Fig. 3. When it is desired to support a garment, for example, a pair of trousers 24, it merely becomes necessary to grasp the sides 35 of the loop 15 and draw the same apart slightly and at the same time raise the loop to horizontal position, as indicated at Fig. 2. This will cause the ends 16a, 16b of the overlapping portions 15a, 15b to approach each other, as indicated at Fig. 40, and cause the same to be freed of the inner ends of the in-turned ends 11a of the bar 10, and permit the loop 15 to be raised to horizontal position. When the pull upon the opposite sides of the loop 15 is thereupon released the ends 16a, 45 16b will resume their normal or distended positions and rest upon the in-turned ends 11a, of the bar 10, and thus support the loop in horizontal position. Hereupon the upper edge of the trousers is engaged with the pointed ends of the hooks 20, or between the jaws 25 of the clamping device, shown at Fig. 4, to support the garment in distended or open form to facilitate the drying and airing thereof.

Having thus described my said invention what I claim and desire to secure by Letters Patent is:

1. A garment hanger comprising a longitudinal member adapted for securing to a rigid support and having inturned ends, a frame member including a resilient loop having its ends extending therefrom in spaced relation and pivotally engaging said longitudinal member and normally distended in engagement with said inturned ends for supporting said loop in horizontal position, said loop being actuatable to free the ends thereof from the inturned ends of said first-named member to permit said loop to be adjusted to vertical position, and garment supporting means on said loop.

2. A garment hanger formed of wire comprising a longitudinal member adapted for securing to a rigid support and having inwardly-turned ends disposed forwardly of said longitudinal member, a resilient loop having its ends extending therefrom in spaced relation and pivotally embracing said longitudinal member intermediate the inturned ends thereof, said loop ends being normally distended into engagement with the ends of said longitudinal member and its ends supported by the inturned ends of said longitudinal member for supporting said loop in horizontal position, and said loop being yielding to free the ends thereof of their engagement with said inturned ends to permit of said loop being adjusted to vertical position when not in use, and attaching devices on said loop engageable with a garment to support the garment disposed upon said loop.

3. A garment hanger formed of wire comprising a longitudinal member adapted for securing to a rigid support and having aligned, in-turned ends disposed forwardly of said longitudi-

nal member, a resilient loop having its ends arranged in overlapping relation and terminating in rearwardly extending spaced-apart portions having eyes pivotally embracing said longitudinal member, said loop ends being held normally distended into engagement with the ends of said longitudinal member and supported by said in-turned ends for supporting said loop in horizontal garment-supporting position, and said loop being actuatable to free the ends thereof of their engagement with said inturned ends to permit of said loop to be adjusted to vertical position, and attaching devices engageable with a garment to support the same in distended form upon said loop.

4. In a garment hanger, a member adapted for securing to a support and having inturned portions, a frame member including a resilient loop having its ends extending therefrom in spaced relation and normally distended in engagement with said inturned portions for supporting said loop in a horizontal position, said loop being actuatable to free the ends thereof from said inturned portions, to permit said loop to be adjusted to vertical position.

5. In a garment hanger, a member adapted for securing to a support, said member having inturned portions, a loop having end portions extending therefrom in spaced relation, said loop being normally disposed with its ends supported by the said inturned portions for supporting said loop in a horizontal position, and being actuatable to free the ends thereof of their engagement with said inturned portions, to permit of said loop being adjusted to vertical position.

JOEL SCHLANK.
